No. 37,074.

Patented August 9, 1904.

UNITED STATES PATENT OFFICE.

MAX F. HAHN, OF ST. LOUIS, MISSOURI, ASSIGNOR TO ANHEUSER-BUSCH BREWING ASSOCIATION, OF ST. LOUIS, MISSOURI, A CORPORATION.

DESIGN FOR A DECALCOMANIA-TRANSFER.

SPECIFICATION forming part of Design No. 37,074, dated August 9, 1904.

Application filed April 25, 1904. Serial No. 204,912. Term of patent 7 years.

To all whom it may concern:

Be it known that I, MAX F. HAHN, a citizen of the United States, residing at St. Louis, in the State of Missouri, have invented a new, 5 original, and ornamental Design for a Decalcomania-Transfer, of which the following is a specification, reference being had to the accompanying drawing, which shows a face view of my new design for a decalcomania-transfer.

What I regard as new, and desire to secure to by Letters Patent, is—

The ornamental design for a decalcomania-transfer, as herein shown.

MAX F. HAHN.
